Patented Oct. 28, 1958

183,820

COLOSTOMY IRRIGATOR

Richard H. Yohe, Salem, Ill.

Application October 3, 1956, Serial No. 48,207

Term of patent 14 years

(Cl. D83—1)

Figure 1 is a front elevational view of a colostomy irrigator showing my new design;

Figure 2 is a perspective view thereof on a reduced scale taken from the top and right side of Fig. 1;

Figure 3 is a rear elevational view; and

Figure 4 is a top plan view thereof.

I claim:

The ornamental design for a colostomy irrigator, as shown.
